UNITED STATES PATENT OFFICE.

LEWIS C. BAYLES, OF JOHANNESBURG, TRANSVAAL, AND ALBERT H. TAYLOR, OF EASTON, PENNSYLVANIA, ASSIGNEES TO INGERSOLL-RAND COMPANY, OF NEW YORK, N. Y., A CORPORATION OF NEW JERSEY.

PRESSURE-FLUID TOOL

1,114,335.

Specification of Letters Patent.

Patented Oct. 20, 1914.

Application filed July 8, 1910. Serial No. 571,045.

To all whom it may concern:

Be it known that we, LEWIS C. BAYLES and ALBERT H. TAYLOR, citizens of the United States, and residents, respectively, of Johannesburg, Transvaal, and of Easton, in the county of Northampton and State of Pennsylvania, have invented a new and useful Improvement in Pressure-Fluid Tools, of which the following is a specification.

Our invention relates to certain improvements in the construction, form and operation of the several parts of a pressure fluid actuated tool such, for instance, as a hammer drill whereby the construction is materially simplified and the cost of the same cheapened.

With these ends in view, our invention comprises a pressure fluid actuated tool in which the manually operated controlling or throttle valve for controlling the admission of fluid pressure to both the feed and the tool is located in the valve chest. In this chest is also located the valve for actuating the tool piston and the valve chest also carries the handle for rotating the tool.

A practical embodiment of our invention is represented in the accompanying drawings, in which—

Figure 1 represents the tool in side elevation, Fig. 2 is a similar view taken at right angles to Fig. 1, Fig. 3 is a view similar to Fig. 2 with the valve chest and part of the hammer cylinder and feed cylinder shown in longitudinal central section, and Fig. 4 is a section taken in the plane of the line A—A of Fig. 3, showing the location of the throttle valve and the rotating handle.

The hammer cylinder is denoted by 1; its piston hammer by 2; the front head by 3 and the tool steel by 4. The valve chest is denoted by 5 and is located at the inner end of the hammer cylinder 1, a plate 6 being interposed between the chest and hammer cylinder, which plate forms a cover for the valve chest.

The means for feeding the tool consists of a cylinder 8 in which is located a piston 9. This piston is provided with a tail piece 10 for engaging any suitable support at the rear of the tool.

Bolts 11 are provided for holding the tool cylinder, feed cylinder and interposed valve chest together. These bolts pass through a flange 12 at the outer end of the

feed cylinder 8, through holes in the valve chest 5 and through holes in the plate 6, if such a plate is used, and then through a flange 13 at the inner end of the hammer cylinder 1, thus forming a simple and effective means for locking the parts together and making the operation of taking the tool apart, a very simple one.

The valve 7 for controlling the operation of the piston hammer is located in the valve chest 5 and may be of any desired form. A main pressure fluid inlet passage 14 is provided for the valve 7, which passage is arranged to be brought into and out of communication with the main pressure fluid supply passage 15 by means of a manually operated controlling or throttle valve 16, as will be described later. The motive fluid exhaust passage 17 leads to external atmosphere and is at all times in open communication with the piston hammer operating valve 7. The manually operated pressure fluid controlling or throttle valve 16 is seated in the valve chest 5 which forms a housing therefor. This throttle valve is provided exterior to the valve chest with an operating handle 18. This throttle valve 16 has a central chamber 19 which is always in open communication with the fluid pressure supply passage 15, as clearly shown in Fig. 4.

A port 20 in the throttle valve 16 is arranged to open and close communication between the passages 14 and 15 and a port 21 is arranged to open and close communication between the passage 15 and a passage 22 leading to the interior of the feeding cylinder 8. These ports are so arranged that pressure fluid may be fed to the tool feeding device and to the tool controlling valve to insure the proper working of the mechanism.

A tool rotating handle 23 is secured to the valve chest 5 as follows:—The inner end of the handle is provided with a screw threaded portion 24 and adjacent thereto with a tapered portion 25. The valve chest 5 is provided with a tapered hole therethrough for receiving the tapered portion 25 of the handle 23. A nut 26 is engaged with the screw threaded end 24 of the handle 23 exterior to the valve chest for drawing the tapered portion of the handle into snug engagement with its seat.

While we have shown this invention as applied to a pressure fluid actuated hammer drill, it is to be understood that the invention may be equally well applied to fluid pressure tools of various kinds.

What we claim is:—

1. In a pressure fluid tool, the tool cylinder, its piston, a tool feeding cylinder, its piston, a valve chest located between the two cylinders, a plate interposed between the valve chest and tool cylinder forming a cover for the valve chest and bolts engaging the two cylinders valve chest and plate for securing the valve chest, plate and cylinders in assembled adjustment.
2. In a pressure fluid tool, the tool cylinder, its piston, a tool feeding cylinder, its

piston, a valve chest located between the two cylinders, a plate interposed between the valve chest and tool cylinder forming 20 a cover for the valve chest and bolts passing through the valve chest and plate and engaging the two cylinders for securing the valve chest, plate and cylinders in assembled adjustment.

In testimony, that we claim the foregoing as our invention, we have signed our names in presence of two witnesses, this fifth day of July, 1910.

LEWIS C. BAYLES.

ALBERT H. TAYLOR.
